UNITED STATES PATENT OFFICE.

JOHN A. HOLMQUIST, OF WOODLAWN, PENNSYLVANIA.

MACHINE FOR MAKING WIRE REELS.

Original application filed December 30, 1922, Serial No. 609,842. Patent No. 1,501,343. Divided and this application filed October 29, 1923. Serial No. 671,411.

To all whom it may concern:

Be it known that I, JOHN A. HOLMQUIST, residing at Woodlawn, in the county of Beaver and State of Pennsylvania, a citizen 5 of the United States, have invented or discovered certain new and useful Improvements in Machines for Making Wire Reels, of which improvements the following is a specification.

10 My invention relates to machinery for fabricating wire reels of the character shown and described in United States Letters Patent No. 1,375,844, granted me April 26, 1921. This present application is a division of my 15 application for Letters Patent filed December 30, 1922, Serial No. 609,842, on which the Patent No. 1,501,343 was granted July 15, 1924.

In the accompanying drawings Fig. I is 20 a view in plan from above, and Fig. II is a view in vertical and longitudinal section of the machine unit in which my present invention resides. Fig. III is a view to somewhat larger scale and fragmentary, 25 showing in horizontal section a detail of this machine and illustrating its method of operation. Fig. IV is a view in elevation of an initially formed loop, and this loop is the blank upon which the machine of my 30 present invention is adapted to operate. Fig. V shows in similar manner the reel part or element, after it has been shaped in the machine of my present invention. Fig. VI shows another reel part or element also 35 shaped from such a loop or blank as Fig. IV shows. And Fig. VII shows in perspective the completed reel, and in it will be recognized the component parts or elements; there are two parts or elements such 40 as Fig. V shows, and two such as Fig. VI shows.

The machine of my present invention consists essentially of four blocks, 10, 11, 12, and 13, arranged approximately (with qualifications presently to be dwelt upon) in common plane, and arranged in pairs. The blocks of each pair stand opposite one another, on axial lines at right angles one to the other. The opposite blocks 10 and 50 11, on the axial line $a-b$, are stationary; the opposite blocks 12 and 13 reciprocate, approaching, overlapping, and receding again on the axial line $c-d$. The arrangement of these blocks on the horizontal table top 14, 55 the reciprocation of blocks 12 and 13 in

slideways 15, and means for effecting reciprocation are fully illustrated in exemplary manner in Figs. I and II, and do not require minute explanation. Suffice it to remark that the blocks 12, 13, may be caused 60 to reciprocate in slideways 15 in response to rotation of a shaft 16 by means of cams 17 borne on countershafts 18 to which the blocks are connected by links 19.

The blocks 12 and 13 in their range of reciprocation move from the remote position shown in Fig. I, which permits the application of a blank upon blocks 10 and 11, to the overlapped position shown in Fig. V. To permit of this cooperative 70 movement the blocks 12 and 13 are sufficiently offset. The proximate faces of blocks 12 and 13 are the wire-engaging and blank-forming faces, and accordingly they are rounded and grooved. The remote faces 75 of blocks 10 and 11 are rounded. The bases of blocks 10 and 11 are particularly shaped, as shown in Fig. II, to allow an applied blank to come to place inclined slightly from the horizontal, and in such position 80 that its opposite legs may be engaged by the two blocks 12 and 13, advancing as has been explained, in different planes.

When in the course of operation the blocks 12 and 13 are in remote position, shown in 85 Fig. I, a blank A, such as that shown in Fig. IV may be applied, encircling both blocks 10, 11, its ends projecting beyond these blocks and its side members or legs resting upon the widened bases of these 90 blocks, and, in consequence of the minute shaping of the blocks, tipped somewhat from the horizontal. The blocks 12 and 13 close upon a blank so positioned in the machine. The dimensions and relative positions of the 95 shaping parts are so proportioned to the size of the blank, and the power with which the blocks 12 and 13 are advanced is such that the blank engaged by all four blocks, cooperating in the manner sufficiently indicated brings the blank from the initial shape indicated in dotted lines to the full-line shape shown in Fig. V, and imposes that 100 shape permanently upon it. This shape I characterize as "three-eyed," since there are 105 three eyes or openings defined by the bent wire. Fig. III shows the blank B completed and still engaged by the forming instrumentalities. It will be observed that the outer faces of blocks 10 and 11 are pref- 110

erably not blank-forming faces, but merely guiding faces, and that the curvature initially imposed upon the blank at its ends is the curvature which it carries to the completion of the reel. By thus leaving clearance of the ends of the blank, when formed, beyond the outer faces of blocks 10 and 11 (Figs. III) allowance is made for minor irregularities both in size of the blank and in the positioning of the blank in the machine.

While the machine which I here show and describe forms blanks such as that shown in Fig. IV to the particular shape shown in Fig. V, other such blanks are formed to the particular shape shown in Fig. VI. Two shaped blanks of each sort are then assembled and the reel is articulated and formed into a unitary structure by increasing the bends in the members C at the points indicated at *c*, Fig. IV, and forming these bends into the loops or eyes which in Fig. V bear the same reference letter *c*.

I do not dwell here upon the particular features of the reel which give it utility; these are sufficiently considered in the specification of my patent first above mentioned.

I claim as my invention:

1. In a machine for forming reels out of wire, a machine unit consisting of four blocks, two standing opposite one another in stationary positions and adapted to bring to position an endless hoop of wire applied

to them, and two being oppositely reciprocatory between the stationary blocks in parallel planes angled with respect to the plane of a loop resting on the stationary blocks, thereby shaping an applied loop to three-eyed formation.

2. In a machine for forming reels out of wire a machine unit consisting of four blocks, two standing opposite one to another in stationary positions and two oppositely reciprocable between the two first named, the stationary blocks first named being provided with obliquely extending seats whereby the opposite sides of an elongate hoop of wire resting upon them, are maintained in different horizontal planes, and the said reciprocable blocks moving each in the plane in which one side of a loop so positioned extends.

3. In a machine of the character described the combination of the blocks 10 and 11 stationary at an interval opposite one another, the movable blocks 12 and 13, and means for causing the said movable blocks to reciprocate oppositely and simultaneously across the interval between the said stationary blocks.

In testimony whereof I have hereunto set my hand.

JOHN A. HOLMQUIST.
